TENSION CONTROL APPARATUS

Walter E. White, Montreal, Quebec, Canada, assignor to Western Electric Company, Incorporated, New York, N. Y., a corporation of New York

Application July 30, 1936, Serial No. 93,389

7 Claims. (Cl. 242—45)

This invention relates to a tension control apparatus, and more particularly to a control apparatus for a reeling motor to maintain the tension constant on the material being reeled.

5 An object of the invention is to provide an effective and efficient mechanism for controlling the tension on material being advanced.

In accordance with one embodiment of the invention, the capacity of a condenser is varied 10 in accordance with the tension on a strand to control the speed of a reeling motor.

Other objects and advantages will appear from the following description taken in conjunction with the following drawings, in which

15 Fig. 1 is a diagrammatic view of a tension control apparatus embodying the invention;

Fig. 2 is a front elevation of a portion of the apparatus including a diagrammatic view of a tension indicator;

20 Fig. 3 is a side elevation of the apparatus shown in Fig. 2;

Fig. 4 is a detail view of the condenser taken on line 4—4 of Fig. 3;

Fig. 5 is a sectional view taken on line 5—5 of Fig. 4;

Fig. 6 is a diagrammatic view of an alternative type of control motor to be used with the control system of Fig. 1, and

Fig. 7 is a diagrammatic view of a modified form of control system.

The invention is illustrated in Fig. 1 in connection with a tape-up reel 11, driven by a direct current motor 12, to reel a strand 13, after passing through the idler rollers 14 from any suitable source 15, which may represent a wire drawing apparatus, wire coating apparatus, or other source of wire to be wound upon the reel. The idler pulleys 14 are arranged to form in effect a triangle with a pulley 16, Figs. 1 and 2, which is mounted on a support 17 slidably mounted on a vertical bar 18. A cord 19 is attached to the upper end of support 17 and passes over an idler pulley 21 to be attached to a movable plate 22 of a condenser 20. The other end of this plate has a cord 23 secured thereto which passes over an idler pulley 24 and is connected to a spring 25 which tends to continuously urge the plate 22 toward the right as viewed in Fig. 4. The movable plate 22 of the condenser is associated with a fixed plate 26 mounted in an insulating support 27. The plates 22 and 26 are insulated from each other by a suitable dielectric material 28 of mica, or the like. The capacity of this condenser is varied by the relative movement of the condenser plates 22 and 26. Thus, for

instance, when the tension in the strand 13 increases, the pulley 16 will be lowered, shifting the movable plate 22 to the left, as viewed in Fig. 4, to decrease the capacity of the condenser, and when the tension in the strand decreases, pulley 16 will be moved upwardly by the spring 25, moving movable plate 22 to the right, as viewed in Fig. 4, to increase the capacity of the condenser. The plates of condenser 20 are so shaped that the capacity of the condenser 10 changes in proportion to the relative movement of the plates. This condenser forms one arm of an impedance bridge having preferably two fixed condensers 29 in complementary arms, and a variable condenser 31 in the fourth arm. 15

The impedance bridge is energized through a transformer 32 which is in a plate circuit of an oscillator tube 33. This tube is provided with a grid bias 34 and by-pass condenser 35, and the circuit in which it is connected is made regenerative by a coil 36 in its grid circuit, coupled to its energizing transformer 37, and being made a part of both the grid and plate circuits whereby energy in the plate circuit is fed back into the grid circuit, thus causing oscillations to be maintained. The coil 36 is connected in parallel with a tuning condenser 38 for selecting the frequency of the output of tube 33. The plate current for the oscillator tube 33 is provided by a rectifier tube 41 and a filter circuit 42 connected 20 to the output of the rectifier tube. The output of the impedance bridge is connected through an impedance matching transformer 43 to an amplifier circuit comprising a tube 44 preferably of the tetrode type. This tube is provided 25 with a grid bias 45 and by-pass condenser 46, the grid bias being so chosen that the tube has a rectilinear plate current relative to its grid voltage. Tube 44 is energized through a transformer 47 which supplies a rectifier tube 48 from 30 which the rectified current passes through a filter circuit 49 to a resistance 51 to which the plate and screen grid of the tube are connected. While the plate current of tube 44 is preferably 35 rectilinear with respect to its grid voltage, it will 40 be evident that a non-rectilinear characteristic may be used, in which case the movable condenser plate 22 should be of such configuration that a given variation in tension will cause a 45 corresponding variation in the plate circuit of 50 tube 44.

The coil of a relay 52 is connected into the plate circuit of tube 44, and when the tension of the strand is at the selected value, there is just sufficient current passing through the coil

52 to hold its armature in its mid-position. If now the tension in the strand decreases, the current in the plate circuit of tube 44 will decrease and allow the armature of relay 52 to engage its back contact 53. This closes a circuit through a relay 54 from the full wave rectifier 55 preferably of the copper oxide type energized from the transformer 56. The armature of relay 54 is weighted so as to increase the time delay thereof.

10 The closing of the contact of relay 54 closes a circuit through the coil of a slow to operate relay 57. Relay 57 is made slow to operate so that it will not close upon a momentary change in tension of the strand. The closing of the contact of relay 57 closes a circuit through the field coil 58 of a motor 59. The motor 59 adjusts the variable resistance 61 which is in the field coil 62 of reeling motor 12. This motor is also provided with a field coil 63, which supplies the normal excitation for the motor. This excitation

15 may be varied manually by means of a rheostat 64 to change the tension on the strand according to the size of the strand being reeled. The field coil 62, therefore, supplies only the control excitation for the reeling motor 12. When the field coil 58 of motor 59 is energized in response to a decrease in tension, motor 59 rotates in such a direction as to increase the amount of resistance 61 in series with the field coil 62 so as to decrease the excitation and increase the speed of this motor to compensate for the decrease in tension. When the tension on the strand becomes too large, the plate current of tube 44 will increase to such an extent that relay 52 will close

20 on its front contact 65 and energize relay 66, also having a weighted armature. The closure of relay 66 will energize slow to operate relay 67 and when the contacts of relay 67 close, field coil 68 of motor 59 will be energized. This causes the motor 59 to rotate in such a direction as to decrease the amount of resistance 61 in series with the field coil 62 of motor 12, thereby increasing the field excitation of motor 12 to decrease its speed and thereby reduce its tension. Since the compensation for tension variations depends entirely upon the tension, it will be seen that the apparatus will maintain the tension constant regardless of whether the source of supply of the strand 15 delivers the strand at a constant speed or not.

25 The apparatus is also provided with means for maintaining the tension on the strand constant during periods of acceleration and deceleration as during starting or stopping. When the switch 71 is first closed to set the apparatus in motion, the double throw switch 72 is also closed on one of its sets of contacts. This causes the energization of the field coil 73 of a motor 74 through a manually adjustable resistance 75. It will be seen that the current for the armature excitation of motor 12 passes through a variable resistance 76 which is controlled by motor 74. Since it is desired to accelerate the motor 12 at a definite rate, the resistance 76 should be at a maximum when the motor 12 is started. The closing of switch 72 then causes motor 74 to rotate in such a direction as to gradually decrease the amount of resistance 76 in series with the armature of motor 12, so that when the motor 12 reaches

30 normal operating speed, the minimum resistance 76 is in circuit with its armature, at which time the switch 72 is opened. In order to decelerate the motor 12 the double throw switch 72 is closed on its opposite contacts so as to gradually increase the amount of resistance 76 in the arma-

ture circuit of motor 12. The amount of resistance 76 in the armature circuit of motor 12, when it is desired to stop the reeling operation, may thus be increased until it attains a value such that the motor 12 will gradually slow down and come to a stop, whereupon the D. C. supply may be disconnected in any well-known manner. When it is desired to restart the reeling operation, the D. C. source may be reconnected and the switch 72 reversed, thereby to gradually decrease the amount of resistance 76 in the armature circuit of motor 12 to permit sufficient current to flow in the armature circuit to start the motor 12 and gradually increase its speed to the normal operating speed where a minimum amount of resistance 76 will be included in the armature circuit of motor 12, whereupon the switch 72 may be moved to its inoperative mid position until it is again desired to stop the reeling operation.

20 In order to inform the operator of the amount of tension applied to a strand by the apparatus, the support 17 is provided with an upwardly extending arm 77 which carries a brush 78 engaging a commutator 79. Each conducting segment of the commutator is connected to one of a plurality of graduated resistances 81. A meter 82 is connected through a resistance 83 to a common lead 84 connected to one of the commutator segments, and the other side of the meter 30 is connected through a battery 85 to the brush 78. Since the position of the brush 78 depends upon the amount of tension in the strand, it will be seen that one of the resistances 81 or the resistance 83 will be in series with the meter, and since each of these resistances has a different value preferably graduated with respect to the other resistances, the position of brush 78 or the tension in the strand will be indicated by the meter 82. A second meter 86 and a variable 35 resistance 87 may be associated with the battery 85 to adjust the potential at the output terminals of the battery 85.

25 The operation of this embodiment of the invention is as follows: The strand 13, from the source 15, having been strung around the idler pulleys 14 and the pulley 16 and connected to the takeup reel 11, the switches 71 and 72 may be closed, to set the apparatus in operation, it being understood that prior to the closure of the switches 71 and 72 the source of direct current 45 will have been connected to the D. C. leads. In its previous operation, the switch 72 would have been moved to position to increase the resistance in resistance 76 to the point where the motor 12 had stopped. Therefore, when the switch 71 is closed and the switch 72 closed on its contacts, which will drive the motor 74 in a clockwise direction (Fig. 1), the amount of resistance in resistance 76 will be gradually reduced to a 50 minimum, whereupon the motor 12 will gradually accelerate to the desired speed, as determined by the setting of the resistance 64. If the strand 13 being reeled encounters only the proper amount of resistance, the control circuit 55 for motor 59 will remain inactive. However, if the tension in the strand increases beyond a predetermined point, relay 52 will be energized to attract its armature, thereby energizing relays 66 and 67 to connect the field coil 68 of motor 59 to the D. C. lines, thereby decreasing the resistance in resistance 61 and decreasing the speed of motor 12 to slow down the reeling operation. If there is a decrease in tension in the strand 13, the condenser 20 will affect its circuit 75

to cause relay 52 to move its armature into engagement with contact 53, whereupon relays 54 and 57 will be energized to connect the field coil 58 of motor 59 to the D. C. lines, thereby to increase the strength of resistance 61 and increase the speed of motor 12. The condenser 20 and its associated circuit will thus control the tension in the wire until it is desired to stop the reeling operation, whereupon switch 72 may be closed on its contacts, which will cause the field coil 73 of motor 74 to be energized to drive the motor 74 in a direction to gradually increase the resistance in resistance 76 to the point where the motor 12 will stop, whereupon the switch 72 may be moved to its open position, switch 71 opened, and the D. C. source disconnected, whereupon the just described operations may be repeated to cause the apparatus to perform a new reeling operation.

20 The apparatus thus far described is illustrated in connection with a direct current reeling motor. Fig. 6 illustrates the use of an alternating current motor 181 for this purpose. The apparatus enclosed in broken lines in Fig. 6 may be substituted directly for the apparatus enclosed in broken lines in Fig. 1. The stator of motor 181 is shown connected directly across the alternating current line 182. The armature of motor 181 is of the wound type and has a manually adjustable resistance 183 and an automatically adjustable resistance 184 in series therewith. The manually adjustable resistance 183 is adjusted to obtain the desired normal tension of the strand depending upon its size, while the resistance 184 is adjusted by means of a motor 185. Field coils 186 and 187 of motor 185 are energized by the apparatus disclosed in Fig. 1 in the same manner that field coils 58 and 68 of motor 59 are energized in that system, and the speed of motor 181 will, therefore, be controlled in accordance with the tension on the strand.

Fig. 7 illustrates a modified form of the invention in which a take-up reel 101 is driven by a direct current motor 102 to reel a strand 103 from a supply source 104. A pair of idler rollers 105 form in effect a triangle with a roller 106 which is urged in a downward direction by the weight 110. Intermediate the weight and pulley 106 a pair of brushes 108 and 107 are moved by the weight. The brush 108 is associated with an indicator system 109 which is identical with the indicator system described in connection with Fig. 1 and the description of the indicator circuit will, therefore, not be repeated. The brush 107 forms part of the control circuit and is movable along a pair of conducting segments 111 and 112 which are separated by an insulating section 113. If the tension attains too high a value, brush 107 will be moved into engagement with the conducting segment 111 and when the tension becomes too low, it will move into engagement with a conducting segment 112. For automatic tension control a switch 114 is closed. If now the tension is too high, brush 107 will engage the conducting segments 111, and a circuit may be traced from one side 115 of a direct current source of energy through a commutator 116 which is rotated by a motor 117 through a speed reducer so that the commutator will rotate at approximately one revolution per minute. The purpose of the commutator 116 is to prevent hunting of the system, a brush 118 engages the commutator, and from here the circuit passes through brush 107, segment 111, the switch 114 through the back contacts of a relay 119 through the coil of relay 121,

limit switch 122 to the other side 123 of the direct current source. This causes relay 121 to make on its front contact, thereby closing a circuit through the field coil 124 of motor 125. It will be seen that the armature of the reeling motor 102 is connected directly across the direct current source while its field coil 126 is connected to the direct current source through a variable resistance 127. This variable resistance is controlled by the motor 125. The tension being too high when the brush 107 engages the segment 111, motor 125 will be rotated in such a direction as to decrease the portion of resistance 127 in the field coil 126 so as to increase the field energization of motor 102 and decrease its speed. If now the tension decreases to such an extent that the brush 107 engages the conducting segment 112, the coil of relay 119 will be energized through the back contacts of relay 121. The circuit through the coil of relay 119 passes through limit switch 120. The energization of coil 119 will cause the field coil 128 of motor 125 to be energized rotating the arm of the variable resistance 127 in such a direction as to increase the portion of this resistance in series with the field coil 126 of motor 102, thereby decreasing the field energization of motor 102, and increasing its speed. A fixed resistance 129 may be connected across the armature of motor 125 to decrease its speed. It will be seen that limit switches 120 and 122 are actuated by the moving arm of rheostat 127 and prevent the motor 125 from rotating this arm beyond the limits of the rheostat.

If it is desired to manually control the tension in accordance with the indications of the tension indicating system 109, the switch 114 is opened and a pair of manual switches 131 and 132 may be used. Thus, by closing switch 131, relay 119 is energized closing its contacts to energize field coil 128, whereby the resistance 127 will be adjusted to increase the tension, whereas if the switch 132 is closed relay 121 will be energized, closing its contacts to energize field coil 124 whereby the resistance 127 will be adjusted to decrease the tension in the strand.

It is not the intention to limit the arrangement of the bridge to an adjustable condenser since an adjustable inductance or resistance may be substituted for the condenser 20 shown. In this case the fixed condenser in the opposite arm is replaced by a matched inductance or resistance.

The term "strand" as used in the specification and appended claims is intended to embrace sheet or strip material as well as other elongated forms of material capable of being advanced by reels, rollers, or other advancing means.

While the invention has been described in connection with certain specific embodiments thereof, it will be understood that many changes and modifications may be made therein without departing from the spirit and scope of the invention.

What is claimed is:

1. In a strand handling apparatus, motive means for applying a tension to a strand, a variable condenser, means for varying said condenser in accordance with the tension on said strand, and control means including a bridge circuit responsive to the adjustment of said condenser which forms an arm of said bridge circuit for controlling the tension applied to the strand by said motive means.

2. In a strand handling apparatus, motive means for applying a tension to a strand, an impedance bridge including a condenser having rel-

5. *Relatively movable plates, the shape of the plates being such that the output current of the bridge is linear in relation to the movement of the plates, means for moving said condenser plates in response to variations in tension, and means for controlling said motive means in response to the output of said bridge.*

3. In a strand handling apparatus, motive means for tensioning a strand, an impedance bridge including a condenser having relatively movable plates, means for moving said plates in response to tension variations, an amplifier circuit including a thermionic tube for amplifying the output of said bridge, said tube and the shape of the condenser plates being so correlated as to provide a linear output of said tube relative to the movement of the condenser plates, and means for controlling said motive means in response to the output of said tube.

20 4. In a strand handling apparatus, motive
means for applying a tension to the strand, a
condenser variable in response to said tension,
an impedance bridge including said condenser in
one arm thereof, an oscillator for supplying cur-
25 rent to said bridge, and means for controlling said
motive means in accordance with the output of
said bridge.

5. In a strand handling apparatus, a reeling motor, a field coil for supplying the normal excitation for the motor, a manually controlled rheostat for varying the excitation of said field coil to select the normal excitation of the motor, a second field coil for supplying a control excitation to said motor, a second rheostat for controlling the excitation of the second field coil, a reversible motor for operating said second rheostat, a bridge circuit responsive to tension in the strand being handled, means responsive to the output of said bridge for controlling the operation of said reversible motor, and a circuit operable simultaneously with the operation of said reversible motor for effecting an auxiliary con-

trol over said reeling motor to cause acceleration or deceleration of said reeling motor.

6. In a strand handling apparatus, a reeling motor, a field coil for supplying the normal excitation for the motor, a manually controlled rheostat for varying the excitation of said field coil to select the normal excitation of the motor, a second field coil for supplying a control excitation to said motor, a second rheostat for controlling the excitation of the second field coil, a reversible motor for operating said second rheostat, a bridge circuit responsive to tension in the strand being handled, means responsive to the output of said bridge for controlling the operation of said reversible motor, and a circuit operable simultaneously with the operation of said reversible motor for effecting an auxiliary control over said reeling motor to cause acceleration or deceleration of said reeling motor, including a motor driven rheostat in series with the armature of said reeling motor. 15 20

7. In a strand handling apparatus, a reeling motor, a field coil for supplying the normal excitation for the motor, a manually controlled rheostat for varying the excitation of said field coil to select the normal excitation of the motor, a second field coil for supplying a control excitation to said motor, a second rheostat for controlling the excitation of the second field coil, a reversible motor for operating said second rheostat, a bridge circuit responsive to tension in the strand being handled, means responsive to the output of said bridge for controlling the operation of said reversible motor, a circuit operable simultaneously with the operation of said reversible motor for effecting an auxiliary control over said reeling motor to cause acceleration or deceleration of said reeling motor, including a motor driven rheostat in series with the armature of said reeling motor, and a switch for controlling the operation of said last mentioned rheostat. 25 30 35 40
